Primary Examiner — Lilyana Bekic*Assistant Examiner* — Carson Jean Bendel(74) *Attorney, Agent, or Firm* — Millen, White, Zelano & Branigan P.C.; Ryan R. Pool(57) **CLAIM**

The ornamental design for a trash can as shown and described.

DESCRIPTION

FIG. 1 is a front perspective view of the trash can showing my new design.

FIG. 2 is a front view thereof.

FIG. 3 is a back view thereof.

FIG. 4 is a side view thereof.

FIG. 5 is another side view thereof.

FIG. 6 is top view thereof; and,

FIG. 7 is bottom view thereof.

The broken lines in the drawings illustrate portions of the trash can which form no part of the claimed design.

1 Claim, 7 Drawing Sheets(56)
